DISPENSING CONTAINER FOR TISSUES

Charles A. Lassine, Memphis, Tenn., assignor to
Kimberly-Clark Corporation

Filed Nov. 7, 1974, Ser. No. 521,368

Term of patent 14 years

Int. Cl. D6—91

U.S. Cl. D6—98

FIG. 1

FIG. 2

FIG. 3

FIG. 4

FIG. 5

FIG. 6

FIG. 1 is a perspective view of a dispensing container for tissues showing my new design;

FIG. 2 is a top plan view;

FIG. 3 is an end elevational view;

FIG. 4 is a front elevational view;

FIG. 5 is a bottom plan view; and

FIG. 6 is an enlarged front perspective view in the open position.

The undisclosed end of the tissue dispenser and the undisclosed rear are mirror images respectively of the end and frontal views shown.

I claim:

The ornamental design for a dispensing container for tissues, as shown and described.
